UNITED STATES PATENT OFFICE

OLBERT C. NOBLE, OF WASHINGTON, PENNSYLVANIA, ASSIGNOR TO TYGART VALLEY
GLASS COMPANY, OF WASHINGTON, PENNSYLVANIA, A CORPORATION OF WEST VIRGINIA

DESIGN FOR A JAR

Application filed May 8, 1933. Serial No. 48,043. Term of patent 7 years.

To all whom it may concern:

Be it known that I, OLBERT C. NOBLE, a citizen of the United States, residing at Washington, in the county of Washington, State of Pennsylvania, have invented a new, original, and ornamental Design for a Jar, of which the following is a specification, reference being had to the accompanying drawing forming a part hereof.

I claim:

The ornamental design for a jar, as shown.

OLBERT C. NOBLE.
